DESIGN FOR A JEWELRY SETTING OR SIMILAR ARTICLE

Ferdinand Eichmuller, Philadelphia, Pa., assignor to Baker & Company, Inc., Newark, N. J., a corporation of New Jersey

Application July 5, 1935, Serial No. 57,530

Term of patent 7 years

To all whom it may concern:

Be it known that I, Ferdinand Eichmuller, a citizen of the United States and a resident of Philadelphia, in the county of Philadelphia and State of Pennsylvania, have invented a new, original, and ornamental Design for a Jewelry Setting or Similar Article, of which the following is a specification, reference being had to the accompanying drawing, forming part thereof.

I claim:

The ornamental design for a jewelry setting or similar article, as shown.

FERDINAND EICHMULLER.
